BAG FRAME AND METHOD OF MAKING IT

William J. Klemp, Maplewood, N. J., assignor to
Karl Oswald, Newark, N. J.

Application July 13, 1934, Serial No. 734,924

6 Claims. (Cl. 153—2)

This invention relates in general to frames for ladies' hand bags, purses, pocket books and the like, the invention being particularly directed to the structure of the frame for the mouth or opening of the bag.

A frame of this general character includes two approximately U-shaped sections which are pivotally connected together at the extremities of their arms and have the bag covering, such as leather or composition fabric secured thereto, so that upon relative pivotal movement of the sections, the bag may be opened and closed. Inasmuch as such frames are subjected to hard usage, particularly to repeated and severe strains in opening and closing of the bags, it is highly desirable that the frames be very strong, but at the same time it is desirable that the frames be light in weight so that they shall not constitute too great a burden to the persons carrying them. It has been customary in the art to make such frames by spot welding or riveting pieces of metal together, or by bending metal and then riveting or spot welding additional pieces at the bends to reinforce the frame sections at the bends or angles thereof. Such structures and methods are expensive both in cost of materials and labor.

An important object of my invention is to provide a novel and improved bag frame and method of making it whereby the frame shall be formed of one piece of sheet material, so as to obviate the necessity for spot welding or riveting, and shall be strong and durable in use and inexpensive to manufacture.

Another object is to provide a novel and improved blank for a bag frame section consisting of a single strip of sheet material which can be easily and quickly fabricated by simple bending operations into a complete strong durable and inexpensive frame section.

Other objects, advantages and results of the invention will appear from the following description, when read in connection with the accompanying drawings.

Referring to said drawings in which corresponding and like parts are designated throughout the several views by the same reference characters,

Figure 1 is a plan view of a blank for a bag frame section embodying my invention.

Figure 2 is an edge elevation thereof.

Figure 3 is a plan view showing the frame section in the form in which it appears after the first series of bending operations on the blank.

Figure 4 is a side elevation of the structure shown in Figure 3.

Figure 5 is a fragmentary longitudinal vertical sectional view on the line 5—5 of Figure 3.

Figure 6 is a transverse vertical sectional view on the line 6—6 of Figure 3.

Figure 7 is an enlarged fragmentary perspective view of the channel formed from the blank prior to bending of the channel.

Figure 8 is a top plan view of two of the channels pivotally connected together after having been subjected to the first transverse bending operation.

Figure 9 is a side elevation of the structure shown in Figure 8.

Figure 10 is a top plan view of the completed bag frame.

Figure 11 is a side elevation thereof showing a portion of the bag cover applied to the frame.

Figures 12 and 13 are enlarged fragmentary vertical sectional views on the lines 12—12 of Figure 10 showing the successive steps in bending the channel transversely.

Figure 14 is a similar view on the line 13—13 of Figure 10, and

Figure 15 is a fragmentary perspective view showing the manner of attaching the cover to the frame.

Specifically describing the illustrated embodiment of the invention, the bag frame comprises two identical sections A and B which are approximately U-shaped, each including a main portion C and two end portions D approximately perpendicular to the main portions. The extremities of the end portions D are pivotally connected at E as by suitable hollow rivets so that the two sections may swing toward and from each other.

Each frame section is formed of a blank 1 of bendable sheet material for example sheet metal, which has pivot ears 2 at its extremities to receive the hollow rivets E. One longitudinal edge of the blank has two V-shaped notches 3 spaced longitudinally thereof; and two openings 4 are formed in the blank in alignment with each notch 3 transversely of the strip, said openings also being spaced from each other in alignment transversely of the strip. Preferably the openings are triangular as shown, and the adjacent sides 5 of the openings of each pair are parallel to each other and extend longitudinally of the strip as clearly shown in Figure 1. After the blank has been formed as described, it is bent longitudinally along the inner ends of the notches 3 as indicated at 6 and along the edges of the openings 4 adjacent the notches as at 7, and then along the adjacent sides 5 of the openings as at 8 and 9.

respectively. The blank is thus formed into a channeled strip having two channels provided with a common side wall 10 and facing in opposite directions, as clearly shown in Figures 6 and 7. 5 The openings 4 are disposed in opposite relation in the side walls of one of the channels and adjacent the base 11 of the channel, while the notches 3 are disposed in the outer side wall of the other channel with their inner portions terminating adjacent the base 12 of said channel. The notches 3 and openings 4 are thus disposed in alinement or juxtaposition transversely of the strip.

Two of the strips are then connected together 10 by the hollow rivets E and arranged in side by side relation as shown in Figure 8. The two strips may then be simultaneously bent transversely at the openings 4 and notches 3 as shown in Figure 9 so as to form in effect a one-piece mitered joint. During this bending operation, the portion of the base 11 of the channel having the openings 4 is doubled as shown at 13 on Figure 12, 15 along the adjacent sides of the openings 4, so that the other sides of the openings are brought 20 into close relation, and the sides of the notches 3 are brought together as shown in Figures 12 and 14 respectively. This bending operation forms one of the end portions D of the bag frame and the other end portion is formed by bending 25 the strip in the same manner at the other openings 4 and notches 3. Thereafter, the doubled portions 13 of the base 11 of the channel are bent or clinched tightly against the adjacent areas of the base of the channel as indicated at 30 35 14 in Figure 13. This completes the bag frame.

From the foregoing, it will be observed that the bag frame comprises two identical sections, each 40 of which is formed of a single piece of sheet material, and that the frame can be formed 45 easily and quickly and inexpensively by a small number of simple stamping and bending operations. The junctures of the main portions C and the end portions D of the frame sections are reenforced by the doubled portions 14 of the 50 bases of the channels and effectually resist bending of the end portions relative to the main portions of the frame sections under the most severe strains incident to use of a bag. There is no 55 any projections or rough edges to hinder the application of the cover to the frame.

A cover may be applied to the bag frame in the usual way, for example by turning under the edge of a covering piece F as indicated at G in 55 Figure 15 and clamping said turned edge in the outer channel of the frame section.

While I have shown and described the invention as embodied in certain specific details of structure it should be understood that this is primarily for illustrating the principles of the invention and that many modifications and changes may be made in the details of structure without departing from the spirit or scope of the invention.

Having thus described my invention, what I claim is:

1. A blank for a bag frame section comprising a strip of bendable sheet material having spaced V-shaped notches on one longitudinal edge and a pair of triangular openings in alinement with and spaced from each notch and each other transversely of said strip, each triangular opening of each pair having one side parallel to one side of the other opening of the same pair and extending longitudinally of the strip. 5

2. The steps in the method of making a bag frame section, consisting in forming a notch in one longitudinal edge of a strip of ductile material, forming two openings in said strip in alinement with and spaced from said notch and each other transversely of the strip, bending the strip 10 along longitudinal lines between said notch and one of said openings and along the adjacent sides of said openings to form two channels having a common wall and facing in opposite directions, and then bending said strip transversely through 15 20 said openings and said notch.

3. The method set forth in claim 2 wherein said notch is made of V-shape, and each of said openings is made triangular with one side thereof 25 parallel to one side of the other and extending longitudinally of the strip.

4. The steps in the method of making a bag frame section, consisting in forming a notch in one longitudinal edge of a strip of ductile material, forming two openings in said strip in alinement with and spaced from said notch and each other transversely of the strip, bending the strip 30 along longitudinal lines between said notch and one of said openings and along the adjacent sides of said openings to form two channels having a common wall and facing in opposite directions, then bending said strip transversely through said 35 openings and said notch, and then bending against the base of the corresponding channel the portion of the material between said openings which has been displaced by said transverse bending of the strip. 40

5. The method set forth in claim 2 wherein said notch is made of V-shape, and each of said openings is made triangular with one side thereof parallel to one side of the other and extending longitudinally of the strip, and with the additional step of bending against the base of the corresponding channel the portion of the material between said openings which has been displaced 50 by said transverse bending of the strip. 45

6. A bag frame section of sheet material having a main portion and two end portions disposed in angular relation to the main portion and including two channels having a common wall and facing in opposite directions, said common wall and the side walls of one channel having mitering openings extending to the base of the channel at the junctures of said end portions with said main portion, the portions of the base of said channel at said junctures being doubled and pressed against the adjacent areas of the base, and the side wall of the other channel having mitering notches in alinement with said mitering openings transversely of said channels. 55 60

WILLIAM J. KLEMP.
